(57) **CLAIM**

We claim the ornamental design for a self service transaction terminal, as shown and described.

DESCRIPTION

FIG. 1 is a left front perspective view of a self service transaction terminal showing our new design, the undislosed rear is not part of the claimed design;

FIG. 2 is a right front perspective view thereof, the undislosed top and bottom are not part of the claimed design;

FIG. 3 is a right side view; and,

FIG. 4 is a left side view.

Surfaces not shown do not form a part of the claimed design.
